(57) **CLAIM**

The ornamental design for a structural member, as shown and described.

DESCRIPTION

FIG. 1 is a front perspective view of a first embodiment of a structural member showing my new design;

FIG. 2 is a front view thereof showing my new design;

FIG. 3 is a rear view thereof showing my new design;

FIG. 4 is a left side view thereof showing my new design;

FIG. 5 is a right side view thereof showing my new design;

FIG. 6 is a top view thereof showing my new design; and,

FIG. 7 is a front perspective view of a second embodiment of a structural member, shown in an environment of use.

The broken lines are shown for the purpose of illustrating environmental subject matter and portions of the article, none of which form part of the claim.

The article is shown with a symbolic break in its length. The appearance of any portion of the article between the break lines forms no part of the claimed design.
